UNITED STATES PATENT OFFICE.

FRANK A. PATTERSON AND CARL REINECKE, OF MAPLEWOOD, MISSOURI.

ELECTRIC IRON.

Application filed May 24, 1922. Serial No. 563,256.

To all whom it may concern:

Be it known that we, FRANK A. PATTERSON and CARL REINECKE, both citizens of the United States, and residing at Maplewood, 5 St. Louis County, Missouri, have invented a certain new and useful Improvement in Electric Irons, of which the following is a specification.

This invention relates to electric smoothing irons, such as are used for manually ironing clothes.

One of the objects of this invention is to provide a smoothing iron, which may be electrically heated, and the heating of which 15 may be regulated in accordance with the operation of the iron.

Another object of this invention is to provide such an electrically heated iron, in which the heating current may be applied 20 during the time that the iron is in operation and may be automatically cut off when the iron is not in operation.

Another object of this invention is to provide such an automatically controlled iron, 25 in which the automatic feature may be eliminated and the iron heated continuously.

Further objects will appear from the detail description taken in connection with the accompanying drawing, in which:

30 Figure 1 is a side view in elevation of an iron embodying this invention;

Figure 2 is a section on line 2—2, Figure 1;

Figure 3 is a section on line 3—3, Figure 2; and

Figure 4 is a detail of the means for holding the electric circuit closed.

Referring to the accompanying drawing, the iron comprises a bottom plate 1, usually 40 of iron or other suitable material, which may be heated up and which will hold a considerable quantity of heat for use in the ironing operation.

Mounted in any usual and approved manner on the bottom plate 1 is a heating element 2 of any usual design. Such an element usually comprises a conducting resistance strip arranged in a tortuous path but lying close to the plate 1, being insulated 45 therefrom and from the cap 3 by means of which it is clamped to the plate 1. The ends of the strip forming the heating element 2 may be brought out at the rear of the iron as shown at 4 and 5 to form terminals for 50 connecting the heating element 2 to the circuit.

Mounted on the cap 3 is an insulating block 6 upon which is mounted a conducting plate 7 equipped with a contact button 8 arranged to make contact with a similar and 55 oppositely disposed button 9 mounted on a spring switch blade 10 suitably mounted upon the casing 11 but insulated therefrom. The casing 11 is mounted on the bottom plate 1 to form therewith a hollow base within 60 which the above described parts are housed. The buttons 8 and 9 may be of tungsten or other suitable material which will not be corroded by the arcing which usually takes place upon making and breaking an electric 65 circuit. The blade 10 is arranged so that it will naturally hold the contacts 8 and 9 separated from one another by virtue of its resiliency. Mounted to slide vertically in the casing 11 is a plunger rod 12 which rests at 70 its lower end upon the spring 10. This rod extends through the casing 11 and projects a short distance above the upper surface thereof. Depression of the rod 12 will cause the contact 9 to engage the contact 8 so as 75 to close the circuit therebetween. The strip 7 may be soldered or otherwise electrically connected to the terminal 4. The terminal 5 may be connected to one of the terminals 13 to which the attachment plug may be connected. The other attachment terminal 14 may be connected to the spring 10 of the switch. Thus by closing the contacts 8 and 9, a circuit is established through the heating element 2.

The casing 11 is mounted upon the bottom plate 1 by means of clamping screws 15 or other suitable fasteners. Hinged at 16 to the casing 11 is a frame 17 carrying a manipulating grip 18. The frame 17 is supported near its rear end by a spring 19 mounted in a depression in the casing 11 as indicated in Figure 3 and confined by a screw 20, the head of which limits the upward movement of the frame 17. The frame 100 17 also carries a plate 21 which extends laterally therefrom and is positioned over the end of the plunger 12 so that depression of the grip 18 against the tension of the spring 19 will depress the plunger 12, so as to close 105 the contacts 8 and 9. Thus the circuit through the heating element 2 will be closed whenever pressure is applied to the grip 18, and will be opened whenever such pressure is relieved.

Hinged at 22 on the casing 11 is an angularly shaped arm 23 having a manipulative

handle 24. After depressing the grip 18, the arm 23 may be swung about the pivot 20 into the position shown in Figure 4, with its angular portion over the frame 17 and its notched end 25 engaging the screw 20. With the arm 23 in this position, the frame 17 will be held in depressed position and the contacts 8 and 9 will be held closed so that the circuit through the heating element 2 will be maintained so long as the latch 23 is maintained in position.

It will thus be seen that as long as the iron is in operation, the circuit through the heating element 2 will be closed by depression of the grip 18 so as to close the contacts 8 and 9. Heat will, therefore, be supplied to the iron throughout the time during which heat is being extracted therefrom by the ironing operation. Upon setting the iron aside and releasing the grip 18, the heating element is cut out so that the heating thereof will cease. Said element is cut in again as soon as operation is resumed. For heating the iron preliminary to beginning the ironing operation or at such times as the extraction of heat has been more rapid than the supply thereof, the arm 23 may be swung into position as shown in Figure 4, so as to maintain the circuit through the heating element and the iron may be heated up to any desired temperature.

It is obvious that various changes may be made in details of construction without departing from the spirit of this invention; it is, therefore, to be understood that this invention is not to be limited to the specific details shown and described.

Having thus described the invention, what is claimed is:

1. An electric iron, comprising, a base adapted to provide a casing, a heating element therein, a plug receptacle thereon, an

iron-manipulating grip having a solid frame and pivoted forwardly on said base so as to move toward and from the same, a switch for said element mounted within said base, connections from said switch adapted to be engaged by said frame to close said switch when said grip is depressed, and selective means for holding said grip in depressed position in order to maintain said switch closed.

2. An electric iron, comprising, a base adapted to provide a casing, a heating element therein, an attachment receptacle on the rear of said base, an iron-manipulating grip pivoted forwardly on said base and attached rearwardly thereon for limited movement on said pivot, a switch within said base, and connections to said switch positioned rearwardly of said base and adapted for engagement by said grip, whereby said element may be cut in when said grip is held down and cut out when said grip is released.

3. An electric iron, comprising, a base adapted to provide a casing, a heating element therein, an attachment receptacle on the rear of said base, an iron-manipulating grip pivoted forwardly on said base and attached rearwardly thereon for limited movement on said pivot, a switch within said base, connections to said switch positioned rearwardly of said base and adapted for engagement by said grip, whereby said element may be cut in when said grip is held down, and cut out when said grip is released, and means for holding said grip down in order to maintain said switch closed.

In testimony whereof we affix our signatures this 6th day of May, 1922.

FRANK A. PATTERSON.
CARL REINECKE.
